FUSE PLUG

Paul F. Dieffenbacher, Klamath River, Calif.

Application October 15, 1936, Serial No. 105,815

1 Claim. (Cl. 200—121)

This invention relates to fuse plugs and has for the primary object the provision of a device of this character which will indicate clearly to a person when blown and may be cheaply renewed 5 or conditioned for further use.

With these and other objects in view, this invention consists in certain novel features of construction, combination and arrangement of parts to be hereinafter more fully described and 10 claimed.

For a complete understanding of my invention, reference is to be had to the following description and accompanying drawing, in which

Figure 1 is a vertical sectional view showing a 15 fuse plug constructed in accordance with my invention and illustrating the same in an operative condition.

Figure 2 is a view similar to Figure 1 showing the fuse plug when blown.

Figure 3 is a top plan view illustrating the plug.

Figure 4 is a perspective view illustrating a pivotally mounted keeper.

Figure 5 is a plan view illustrating the fuse element.

Figure 6 is a fragmentary side elevation showing means of detachably connecting the cap to the body of the plug.

Referring in detail to the drawing, the numeral 1 indicates a conventional type of fuse plug body having the usual central contact 2 and metal screw threaded ferrule 3 forming the other contact of the plug. The body 1 has the usual chamber 4 and the contact 2 has a stem 5 extending into the chamber 4 and terminating in a hook 6 to engage with a hook 7 of a fuse element 8. The hook 7 is located at one end of the fuse element while the opposite end is apertured to receive the free end of a spring arm 9. The spring arm 9 is mounted in a wall of the body 1 and has one end electrically connected to the ferrule 3. The fuse element 8 when attached to the hook 6 and to the arm 9 causes the latter to assume a flexed position under tension.

The chamber 4 of the body 1 is closed by a 45 removable cap 10 having lugs 11 to fit in bayonet

grooves 12 formed in the body whereby a simple turn of the cap in one direction will free the latter from the body and a turn in an opposite direction will bring about locking of a cap to the body. The cap 10 has an opening 13 and pivoted in said opening is a keeper 14, one end of which is enlarged, as shown at 15, and projects outwardly of the opening 13 and is provided with an opening 16. The keeper 14 includes the angularly related portions 17 and 18 and the portion 18 extends into the chamber 4. A signal element 19 is secured to the outer surface of the cap and is of resilient formation and may be bent to extend substantially parallel with the cap and engage within the opening 16 of the keeper thereby retaining the signal element in non-signaling position. However, when the fuse element 8 burns out the resilient arm 9 is released engaging the portion 18 of the keeper and imparting pivotal movement thereto which frees the signal element 19, allowing it to swing outwardly from the cap and assume the position as shown in Figure 2, indicating that the fuse element has blown. Due to the fact that the cap can be easily removed from the body the blown fuse element 20 may be removed and a new one substituted in 25 lieu thereof, thereby reconditioning the fuse for further use.

Having described the invention, I claim:

A fuse plug including a body having a chamber 30 and a contact extending therein and a threaded ferrule mounted on said body and acting as a second contact, a spring arm electrically connected to the ferrule and extending into the chamber, a fuse element detachably connected 35 to said arm and to the first contact, a cap detachably connected to the body for closing the chamber and having an opening, a keeper pivoted in said opening, and a spring actuated signal element held in non-signaling position by said keeper and released from said position by the spring 40 arm engaging the keeper when freed of the fuse element due to the latter becoming fused.

PAUL F. DIEFFENBACHER.
